UNITED STATES PATENT OFFICE.

CHARLES DUNCAN, OF MONTREAL, QUEBEC, CANADA.

ELECTRIC SWITCH CONSTRUCTION.

1,401,891.

Specification of Letters Patent. Patented Dec. 27, 1921.

Application filed October 18, 1919. Serial No. 331,711.

To all whom it may concern:

Be it known that I, CHARLES DUNCAN, a subject of the King of Great Britain, and resident of the city of Montreal, in the Province of Quebec and Dominion of Canada, have invented certain new and useful Improvements in Electric Switch Construction, of which the following is a full, clear, and exact description.

10 This invention relates to improvements in electric switches, and the principal object of the invention is to provide a switch of the tumbler type which may be manufactured and sold at a low cost, and which will be durable and efficient in operation.

15 A further object is to provide a switch so constructed that the working parts are accessible only from the back of the switch so as to be normally guarded against being tampered with.

20 The main consideration in the construction of tumbler and other switches, which are designed to be used by persons unskilled in the handling of electrical apparatus, is a quick make and break in order to reduce arcing to a minimum. For this reason springs are introduced into all switches of this type and some times serve the further purpose of holding the switch in either open or closed 25 position. It therefore develops that failure of the spring will result in such slow operation of the switch that it soon becomes burned out or in the switch becoming inoperative by reason of its inability to remain 30 either open or closed. In a great many tumbler switches the mechanism of the switch takes up so much room that the porcelain base is necessarily weak in order to keep the switch within reasonable limits of 35 size and the screw and conductor passages are formed through the base in what space is available without regard to their proper placing from a point of view of strength and accessibility.

40 According to the present invention the switch mechanism is of extremely simple and compact design enabling an extremely strong porcelain base to be provided without increasing the size of the switch beyond 45 normal. The mechanism is so arranged that an ordinary helical spring in tension provides a resilient element. The screw and conductor passages are located clear of the mechanism and with proper regard for the 50 strength of the base and the security of attachment.

In the drawings which illustrate the invention:

Figure 1 is a vertical sectional view of a tumbler switch constructed according to this 60 invention.

Fig. 2 is a fragmentary, vertical, sectional view at right angles to Fig. 1.

Fig. 3 is a top plan view of the switch with the cap removed. 65

Fig. 4 is a bottom plan of the switch with the back plates removed.

Fig. 5 is a fragmentary plan view of the casing as it appears when in position.

Referring more particularly to the drawings, 11 designates a porcelain base having a centrally disposed, rectangular aperture 12 formed therethrough, above which is a bridge 18 apertured at 14 for the passage of the switch-throw lever. Screw passages 15 are 70 provided in the plane of oscillation of the throw lever as near as possible to the periphery of the base, so that the base is secured in a manner best calculated to withstand the 75 stresses imposed by the operation of the switch. Conductor passages 16 are formed one at each side of the central aperture 12 and entirely clear of all working parts of the switch. These passages are each approximately equidistant between the passages 15. 80 A pair of recesses 17 are formed in the base, one on each side of the central aperture 12 and adjacent conductor passages, for the 85 reception of the terminals and binding posts. Recesses 18 are provided in the sides of the 90 central aperture 12 to form journals for the circuit maker, and recesses 19 are formed in the sides of the slot 14 for the reception of the switch lever pivot. A recess 20 is 95 formed around the central aperture 12 at the bottom of the base to receive the back cover.

The terminals 21 and binding posts 22 are secured together and to the switch base by the usual screws 23 having their heads located at the bottom of the base so as to 100 be inaccessible when the switch is in use. These screws are relieved of all bending stresses by the embedding of the terminals and binding posts in the porcelain base and, therefore, have no tendency to loosen. 105 The terminals are located at one end of the central aperture 12 as clearly seen in Fig. 1. The circuit maker 24 is a substantially U-shaped member of a size to oscillate freely in the recess 12 and to enter forcibly between 110 the terminals. The extremities 25 of the arms of the circuit maker are outwardly

turned to project into the recesses 18 where they act as trunnions supporting the circuit maker. The switch-throw lever 26 occupies the slot 14 and projects at one end beyond the base, the end being threaded to receive a ball 27. The opposite end of the lever is bifurcated and each of the bifurcations 28 is connected through an insulator 29 conveniently by hooking or clenching the arms 10 through the insulator. The lever is supported by a pin 30 which passes through it and rests in the recesses 19 of the bridge. A helical spring 31 is connected at one end to the insulator between the bifurcations 15 28, and is connected at the opposite end to the central part of the circuit maker. It will be noted in Fig. 1 that the lever pivot 30 and circuit maker trunnions 25 are both located in the central transverse plane of 20 the switch and that the attachment of the spring is located in the central transverse plane of each of the lever and circuit makers. The bottom of the aperture 12 is closed by a cover plate 32, preferably of insulating material, and the base and bridge are covered by a cover 33 having insulating lining 34.

While the cap may be attached in any suitable manner, such as by the usual screw thread connection with a metallic member secured to, or forming, a bridge and carrying the throw-lever, it is preferred to adopt the construction illustrated as certain advantages in the assembly of the mechanism are thereby obtained. The pin 30 is U-shaped so that its extremities 35 project above the bridge. These extremities are outwardly turned so as to project beyond the pin receiving recesses 19 of the bridge. The cover 33 is 30 provided with a central aperture 36 at least large enough to permit the cover to be rotated about the U-shaped pin. Diametrically opposite notches 37 are formed in the periphery of the opening 36 to enable the cover to be passed over the out-turned ends 35 of the pin. Bosses or cams 38 are arranged in pairs between the notches 37 and at diametrically opposite points at the edge 40 of the aperture 36. The cams of each pair 45 are spaced apart sufficiently to hold the out-turned pin ends 35 securely between them. In order to facilitate the rotation of the cover 33, necessary to attach and release same and also to conceal the porcelain 50 bridge exposed through the cover opening 36, the top of the bridge may be provided with a metal cap 39 having a centrally disposed crown portion 40 which fits freely within the cover opening 36 and forms a 55 central pivot about which the cover will turn easily. This cap is provided with a centrally disposed cruciform opening 41 for the passage of the lever and pin 30. The cap may be attached to the bridge in any 60 suitable manner which will hold it against

lateral or rotary motion as by the provision of down-turned lugs 42 engaging recesses or flattened portions of the bridge.

The assembly of the switch is extremely simple. The circuit maker and switch-throw 70 lever carrying the insulator are connected by the spring 31 and dropped into place from the back or bottom of the base. The ball 27 is then screwed onto the end of the lever to retain the parts and the lever drawn up 75 until the pin 30 can be inserted. The spring is now slightly in tension and holds the trunnions 25 of the circuit maker in their recesses 18 and also holds the lever pin 30 in the recesses 19. The cover 33 is then dropped 80 onto the base and rotated until the notches 37 pass the out-turned ends 35 of the pin 30. By the application of slight force the cover may now be rotated and the ends of the pin will ride up out of the notches 37 85 onto the cover and will subsequently ride up over and drop between the cams 38 so that the cover will be releasably held against rotation.

The operation of the device is extremely 90 simple. The tension of the spring applied to the unsupported end of the circuit maker tends to throw the circuit maker against one end of the aperture 18 and at the same time inclines the lever until the lever and springs 95 axes are in alinement, as clearly shown in Fig. 1. The spring being in slight tension holds the parts in this position. To operate the switch the lever is oscillated in the usual manner so that its lower end swings past 100 the pivotal point of the circuit maker. In this action the spring is slightly tensioned until its point of attachment to the lever passes the pivotal point of the circuit maker, whereupon, it exerts a pull on the circuit 105 maker to draw it to the opposite end of the aperture 12. This pull is due both to the movement of the lever and to the contractive effort of the tensioned spring. In actual practice the point of connection of the 110 spring and lever gets some considerable distance beyond the pivotal point of the circuit maker before the friction between the circuit maker and the porcelain base is overcome, so that the action of the spring is very positive 115 and the circuit maker is moved with extreme rapidity. Obviously the longer the movement of the circuit maker is delayed and the farther the point of spring connection with the lever passes the circuit maker 120 pivotal point the greater will be the tension of the spring and the quicker the movement of the circuit maker. It will therefore be seen that a certain amount of friction at the 125 pivotal point of the circuit maker is desired. As the elongation of the spring is very little it is possible to use quite a strong spring. The use of a strong spring produces such movement of the circuit maker that it will force itself between quite heavy terminals, 130

thus insuring a very good contact. The operation of the switch is exactly the same whether opening or closing but in the opening movement the friction between the circuit maker and the terminals is added to the friction of the circuit maker mounting, so that an increased tension is obtained in the spring with a consequent increase in the rapidity of action to a point where the arcing period is so brief that the circuit maker and terminals are absolutely prevented from burning.

The spring, in addition to operating the circuit maker, draws down on the lever and holds the extremities 35 of the pivot tightly against the cover 33. It will be noted that these pin extremities 35 are out of parallel with the central portion of the pin being turned toward the cover so that the load of the spring bears only upon the cover and the pin is supported clear of the cap 40 and the porcelain bridge. The result is, that at all times the cover is tightly held and cannot be worked loose by vibration as frequently occurs with the ordinary screwed-on covers. If it is desired to remove the cover it is rotated to force the cams 38 under the pin extremities thereby elongating the spring. After the cams are disengaged from the pin the cover is turned until the pin ends slip into the notches 37, whereupon, the cover may be lifted off. The total rotation either applying or removing the cover is only one-quarter of a revolution so that the cover may be very quickly and easily removed or applied.

While the switch mechanism has been shown in connection with a particular base and cover construction it will be readily understood that such a combination is not essential as the switch mechanism may be applied to other bases and the cover may be secured in any suitable manner entirely independent of the lever pivot and spring.

The advantages of the device are clearly defined and will be readily apparent by any one skilled in the manufacture or installation of such apparatus but for convenience the same are briefly enumerated. The switch has a strong and energetic action which precludes burning of the circuit maker or terminals. The spring is of such type and so arranged that maximum life thereof is insured. The spring will positively hold the circuit maker in either open or closed switch position. The insulation between the handle and lever parts of the switch is ample. The cover will not become loose and fall off exposing the live parts of the switch, nor will the cover fastening become worn by use and inoperative. The cover may be very easily and quickly removed or applied thus simplifying the work of installation. The screw and conductor passages are clear of the other parts of the

switch and the binding posts are readily accessible so that installation is further facilitated. The formation of the base and disposition of the fastenings is such, that the maximum strength is obtained thereby increasing the life of the switch. The bridge conceals the working parts of the switch so that the same are protected against tampering or accidental damage when the cover is off. The parts of the switch may be manufactured with extreme ease and rapidity and at a very low cost. Fewer assembling operations are required than in the manufacture of ordinary switches and these operations are extremely simple.

Having thus described my invention, what I claim is:

1. In a switch, a base having a recess opening from its lower surface, terminals projecting into said recess, a circuit maker 35 oscillatably mounted in the recess and circuit maker operating means projecting into the recess.

2. A device according to claim 1, in which the recess includes laterally directed, aligned 90 extensions thereof forming circuit bearings.

3. A device according to claim 1, in which the circuit maker is a U-shaped member having outwardly turned trunnions at the extremities of its arms journaled in lateral extensions of the recess.

4. A device according to claim 1, in which the circuit maker comprises a U-shaped member pivotally mounted at the extremities of its arms, and in which the operating 100 means is connected to the central part of the circuit maker and lies between the arms thereof.

5. A device according to claim 1, in which the circuit maker and operating means are 105 removable from the recess toward the rear of the base and means engaging the circuit maker operating means and holding the operating means and circuit maker against removal.

6. A device according to claim 1, in which the recess extends in reduced size through the front surface of the base, the operating means only being movable through said recess in combination with a pivot pin passing 115 through the operating means on the front surface of the switch and holding the circuit maker and operating means against escape from the recess.

7. A device according to claim 6, in which 120 recesses are provided at the front surface of the switch for the reception of said pin.

8. In a switch, a base having a centrally disposed aperture, a bridge on the upper surface of the base spanning said aperture, 125 terminals and a circuit maker located in said aperture and rendered inaccessible from the front of the base by reason of said bridge, and circuit maker operating means mounted on said bridge.

9. A device according to claim 8, in which the bridge is provided with a slot extending from the upper surface thereof into communication with the base aperture, and in which the operating means includes a lever insertible at one end through the bridge slot and enlarged at its opposite end to prohibit passage through the slot, and a pivot pin for said lever holding the same against escape from the bridge slot. 10
10. A device according to claim 8, in which the bridge is slotted from the outer surface to the base recess, and in which the circuit maker operating means includes a lever movable in said slot but impassable therethrough, an insulator carried by the lever and a spring connected between the insulator and circuit maker holding the circuit maker to the lever, a pin passing through the lever above the bridge holding the parts in operative position, and a head on the lever holding it against escape from the slot on removal of the pin, whereby the circuit maker is retained with the base. 15
11. A device according to claim 8, in which the base is provided with laterally directed recesses opening from the rear of the base and communicating with the central aperture, the bridge is slotted forming a frontal outlet for the aperture and in which the circuit maker includes trunnions movable into said recesses from the rear of the base, and the operating means includes a lever oscillatable in the bridge slot, a pin passing through said lever at the face of the bridge, and a spring in tension between the lever and circuit maker and holding the circuit maker trunnions in the recess and the pin against the bridge. 20
12. In a switch, a base composed of rough vitreous material, a pair of terminals, a metal circuit maker journaled in the material of the base, whereby the desired frictional resistance to movement of the circuit maker is obtained, and means for operating said circuit maker adapted to act thereon with gradually increasing force until the frictional resistance is overcome. 25
13. In a switch, a pair of terminals, an oscillatable circuit maker, a circuit maker operating member, an operating lever having one end bifurcated, a non-conducting plate provided with end apertures receiving the bifurcations of the lever there-through and connected intermediate said bifurcations to one end of said circuit maker operating member, the opposite end of said member being connected to the circuit maker. 30
14. In a switch, a base, a circuit making and breaking mechanism centrally disposed in said base and including an oscillatable lever, and attaching screw passages formed through said base in the plane of lever oscillation. 35
15. In a switch, a base having a recess, a pair of terminals carried by the base, a circuit maker oscillatable in the recess and journaled in opposite side walls thereof, said circuit maker being engageable with said terminals, and means for operating the circuit maker. 40
16. In a switch, a base having a recess and an integral slotted bridge overhanging said recess, a pair of terminals projecting into said recess, a circuit maker engageable with said terminals and oscillatably mounted in the recess, and a pivotally mounted lever operatively connected to said circuit maker and operating in the slot in the bridge. 45
17. A switch comprising a pair of terminals, an oscillatable circuit maker engageable therewith, an oscillatable lever having a bifurcated end, a non-conducting plate having end apertures through which the bifurcations of the lever are extended and secured, and a tensioned spring having one end secured to said plate between the lever bifurcations and the other end secured to the circuit maker, the points of attachment of the spring being located in the central transverse plane of each of the lever and circuit maker. 50

In witness whereof, I have hereunto set my hand.

CHARLES DUNCAN.
